SYSTEM AND MEANS FOR RETURNING
LEAKAGE FLUID TO A MAIN FLUID
SUPPLYDavid Gregg, Caldwell, N. J., assignor to Bendix
Aviation Corporation, Teterboro, N. J., a cor-
poration of Delaware

Application March 21, 1944, Serial No. 527,509

4 Claims. (Cl. 60—52)

1

My present invention relates to automatic circulating systems and devices, and more particularly to a novel system and means for returning leakage fluid to a main fluid supply.

An object of my present invention is to provide a novel auxiliary tank for collecting leakage fluid, including means for returning such fluid to the main fluid supply.

Another object of my invention is to provide in a single vessel novel means for collecting leakage fluid, including Venturi means for drawing such leakage fluid into the main fluid supply.

Another object of my invention is to provide a novel system for collecting fluid from any device that utilizes fluid pressure to perform work and returning such fluid to the main supply line.

Another object of my invention is to provide a novel compact auxiliary automatic circulating mechanism of great efficiency in comparison to its size and of such simplicity in construction as to adapt it for manufacture and installation at low cost.

The above and further objects and novel features of this invention will more fully appear from the following detailed description and the accompanying drawings wherein like reference characters refer to like parts in the several views. It is to be expressly understood, however, that the drawings are for the purposes of illustration only and are not designed as a definition of the limits of the invention, reference being had for this purpose to the appended claims.

In the drawings:

Figure 1 is a perspective view illustrating my novel auxiliary automatic circulating mechanism and showing in dotted lines the operating parts thereof.

Figure 2 is a sectional view taken along the lines 2—2 of Figure 3.

Figure 3 is a top plan view of Figure 1.

Figure 4 is a diagrammatic view of my novel system for collecting and returning leakage fluid to a main supply tank.

In the drawings there is shown by numeral 1 an auxiliary liquid collection tank or chambered vessel having an inlet conduit 2, as shown in Figure 4, leading from a liquid collection sump 3. The sump 3 is arranged as diagrammatically illustrated in Figure 4 to collect liquid leakage such as oil from a device indicated by numeral 4 such as an automatic pilot for an aircraft or any other device utilizing hydraulic pressure to perform work, where there is leakage of such liquid.

A supply conduit 5 leads from a main supply tank 6 to a pump 7 which may be of the gear

type or any other suitable type. A second conduit 8 leads from the pump 7 to the device 4 to be operated by the hydraulic fluid. A by-pass 9 leads from the outlet of the pump 7 to the inlet of the same. The by-pass 9 has one way control valve 10 of suitable type provided therein and biased in such a manner as to open the by-pass 9 to the passage of liquid from the outlet to the inlet of the pump 7 upon the pump pressure exceeding a predetermined value.

An outlet conduit 11 leads from the device 4 to a venturi 12. A second conduit 13 leads from the outlet of the venturi 12 to the main supply tank 6.

As previously noted the conduit 2 leads from the sump 3 which is arranged in relation to the device 4 so as to collect any leakage from the device 4 and conduct such leakage to the auxiliary collection tank 1.

20 The auxiliary liquid collection tank 1 as best shown in Figures 1, 2 and 3 includes a cup shaped cylinder 1 having a drainage plug 14 for removing liquid from the tank 1 in servicing the same. The tank 1 has provided a top plate 15 arranged to be fastened to the tank 1 by bolts 16. Extending from the top plate 15 into the tank 1 is an inlet conduit 17 fixedly mounted in the top plate 15 and extending from a socket 18 provided in the top plate 15. The socket 18 has provided suitable screw threads 19 for engagement of the open end of the fluid collection conduit 2. A second opening 20 is provided in the top plate 15 venting the interior of the tank 1 to atmosphere.

The venturi 12 extends through the tank 1 from opposite sides thereof and has provided a throat portion 21 opening into which is one end of a suction pipe 22. The opposite ends of the Venturi tube 12 have provided therein suitable screw threads 23 and 24 for engagement of the 30 inlet and outlet conduits 11 and 13 respectively.

The opposite end 25 of the suction pipe 22 opens into the cylinder 1. The opening of the suction pipe 22 at the end 25 is controlled by a suitable flap valve 26.

45 Suitable brackets 27 are affixed at the inner surface of the cylinder wall of the tank 1 at opposite points thereon. The brackets 27 have provided arm portions 28 and 29. Pivotedly mounted between the arm portions 28 and 29 is a rod member 30 to which there is affixed the flap valve 26. A rod 31 is affixed between the arm portions 29 and has pivotally mounted thereon a suitable float 32. The float 32 has provided actuating fingers 33 and 34 positioned at opposite sides of the 50 flap valve 26 for controlling the position of the

55

flap valve 26. The fingers 33 and 34 are so arranged that upon a predetermined quantity of liquid accumulating in the cylinder 1 sufficient to cover the open end of the suction pipe 22 the float 32 will actuate the fingers 33 and 34 so as to open the flap valve 26. Liquid flowing through the Venturi throat 21 under pressure of the pump 7 will create a suction force drawing the liquid accumulated in the tank 1 upward through the open end 25 of the suction tube 22 and into the throat of the venturi 21 so as to return the liquid to the main supply tank 6.

The flap valve 26 and float 32 are so arranged that the end 25 of the suction tube 22 is not opened by the flap valve 26 until such time as the end 25 is submerged under the level of the liquid. Thus no air can be drawn into the suction tube 22 by the venturi 12.

From the foregoing it will be readily seen that I have provided a novel arrangement for returning liquid leakage to the main supply line and an arrangement embodying no moving parts, except a valve and a float which operates intermittently without interference to the hydraulic system and a system far simpler and more economical than the conventional electric or hydraulically operated sump pump.

Moreover, I have provided a novel device which may be readily inserted in any hydraulic system in which there is leakage to be returned to the main supply tank and a device which utilizes the circulation of oil or other suitable fluid to provide the desired suction effect through a venturi or other suitable means for returning the fluid.

Although only one embodiment of the invention has been illustrated and described, various changes in the form and relative arrangement of the parts, which will now appear to those skilled in the art, may be made without departing from the scope of the invention. Reference is, therefore, to be had to the appended claims for a definition of the limits of the invention.

What is claimed is:

1. An automatic circulating system, comprising, in combination, a source of fluid, a pressure pump, a device for utilizing said fluid under pressure of said pump, means for collecting fluid leakage from said device, a single conduit for returning fluid from said device under pressure of said pump to said source, Venturi means provided in said single conduit and operated by said return fluid for drawing the leakage fluid from said collecting means into said return conduit.

2. An automatic circulating system, comprising, in combination, a main liquid supply tank, a pressure pump, a first conduit leading from said supply tank to the inlet of said pressure pump, a second conduit leading from the outlet of said pump to a device supplied by said liquid under pressure of said pump, a third conduit for returning said liquid under pressure of said pump to said main supply tank, an auxiliary liquid tank, a sump for collecting liquid leakage from said device, a fourth conduit for conducting said liquid leakage from said sump to said auxiliary liquid tank, a venturi provided in said third liquid return conduit, a suction conduit leading from the throat of said venturi into said auxiliary tank, valve means controlling the opening of said suction conduit to the liquid in said auxiliary tank, and liquid level responsive means provided in said tank for regulating said valve means, whereby upon a predetermined accumulation of liquid in said tank said valve means may be opened for permitting said liquid to be drawn

from said tank into said venturi for return to said main supply tank.

3. An automatic liquid circulating mechanism, comprising, in combination, a chambered vessel for carrying a liquid medium, a first conduit having formed therein a venturi in which a suction effect is created by movement of a liquid medium through said venturi, said conduit extending through opposite sides of said vessel and being supported by said vessel, a second conduit being supported by said vessel and leading into said vessel for conducting a liquid medium thereto, a tube opening from said vessel into the throat of said venturi, whereby the liquid medium carried within said vessel may be drawn into said venturi for discharge through said first conduit, a first rod extending between opposite walls of said vessel, a flap valve pivoted on said rod for controlling the opening of said tube, a second rod extending parallel to said first rod and extending between the opposite walls of said vessel, a float pivotally mounted on said second rod and responsive to the liquid level in said vessel, actuating members carried by said float for operating said flap valve, whereby the opening and closing of said tube may be intermittently controlled in response to said float.

4. A unitary mechanism, comprising, in combination, a tank for carrying a supply of liquid, said tank having an opening to atmospheric pressure, a first tubular member supported by said tank and extending through the tank, said first tubular member having a restricted portion forming a Venturi throat positioned within the tank, a second tubular member opening into said restricted portion, said second tubular member affixed to said first tubular member and extending downwardly in said tank, said second tubular member being open at the lower end thereof, a flap valve device for closing the open end of said second tubular member, a float device for controlling said flap valve device, a bracket affixed to the inner wall surface of said tank, a first rod carried by said bracket and extending at one side of said second tubular member so as to pivotally support said flap valve device, a second rod carried by said bracket and extending parallel to said first rod at the opposite side of said second tubular member so as to pivotally support said float device, actuating fingers carried by one of said devices and engaging the other of said devices so that said float device may control said flap valve device in accordance with the level of the liquid carried by the tank, and a third tubular member supported by said tank and extending into the tank for supplying liquid thereto.
